UNITED STATES PATENT OFFICE.

RALPH N. ELLIS, OF DES MOINES, IOWA.

DESIGN FOR A WIND-SHIELD FOR MOTOR-CYCLES.

45,525.

Specification for Design.

Patented Mar. 31, 1914.

Application filed November 20, 1913. Serial No. 802,161. Term of patent 7 years.

To all whom it may concern:

Be it known that I, RALPH N. ELLIS, a citizen of the United States, residing at Des Moines, in the county of Polk and State of Iowa, have invented a new, original, and ornamental Design for Wind-Shields for Motor-Cycles, of which the following is a specification, reference being had to the accompanying drawing, forming part thereof.

Figure 1 shows a side elevation of a wind shield. Fig. 2 shows a rear elevation of

same, and Fig. 3 shows a perspective view thereof.

I claim:

The ornamental design for a wind shield for motor cycles, as shown.

Des Moines, Iowa, November 12, 1913.

RALPH N. ELLIS.
